WINDOW PLATFORM

Harry Werkhoven, Chicago, Ill., assignor of one-half to
John P. Werkhoven, Wilmette, Ill.

Application March 2, 1953, Serial No. 339,616

7 Claims. (Cl. 304—24)

The present invention relates generally to scaffolds and more particularly to demountable platforms of the type intended to be placed through a window opening from the inside of a building and to be supported on the sill and by the frame or casing of the window.

It is a general object of the invention to provide a window platform which is portable and readily manipulable so as to facilitate installation, which is of safe, sturdy, yet simple construction, and which permits of economical manufacture.

Another object lies in the provision of a window platform of sill-engaging means which is automatically positioned with respect to frame or casing-engaging means as the latter is adjusted to accommodate windows of various widths.

Still another object of the invention is to provide a window platform structure which is not only adjustable to accommodate windows of different widths, but which includes means for locking the structure in any position of adjustment against accidental dislodgment.

The objects of the invention thus generally set forth, together with other objects and ancillary advantages, are attained by the construction and arrangement shown by way of illustration in the accompanying drawings, in which:

Figure 1 is a central vertical section through a window platform embodying the features of the present invention showing the same in place in a window opening.

Fig. 2 is a top plan view of the illustrative embodiment of the invention in installed condition.

Fig. 3 is a fragmentary vertical section taken substantially in the plane of line 3—3 in Fig. 1.

Fig. 4 is a top plan view of the exemplary window platform in folded condition and with the guard rail assembly removed.

Fig. 5 is a front elevation of the window platform as shown in Fig. 4.

Fig. 6 is a top plan view of the guard rail assembly in folded condition.

Figure 7 is a fragmentary vertical section taken substantially in the plane of line 7—7 in Fig. 2.

While the invention is susceptible of various modifications and alternative constructions, there is shown in the drawings and will herein be described in detail the preferred embodiment, but it is to be understood that it is not thereby intended to limit the invention to the specific form disclosed, but it is intended to cover all modifications and alternative constructions falling within the spirit and scope of the invention as expressed in the appended claims.

As shown in the drawings, the instant invention is embodied in a window platform which is portable in character and is designed to be mounted in window or like openings of various sizes in a building wall to form a support scaffold for a workman cleaning, painting, making repairs, or the like.

Generally, the platform comprises a horizontal step or floor board 10 supported on two generally horizontal sup-

2

port arms 12 pivoted to the underside of the step at opposite ends thereof to extend through a window opening W for engagement with the face of the frame or casing F thereof or building wall surface adjacent the opening.

5 The weight of the platform is adapted to be borne by two short feet 14 extending downwardly from the support arms 12 for engagement with the window sill S. Additionally, the platform is equipped with a guard rail assembly, generally designated 16, which includes a U-shaped hand rail 18 mounted in spaced relation above the step 10 by a pair of standards 20 carried by the step.

When the window platform is to be carried from one window to another, the guard rail assembly 16 is removed and the support arms 12 are folded about their respective pivots into overlapping relation with respect to each other, thus reducing the overall size of the structure. To mount the platform for use on the outside of a window, it is moved out through the window opening W with the guard rail assembly 16 removed and with the support arms 12 in folded or partially folded condition. The support arms are then swung outwardly, away from each other, into their positions for engagement with the window casing F at positions somewhat above the horizontal sill S. After the platform is initially set up in the window opening, the guard rail assembly 16 is then extended through the opening and mounted on the platform.

Each of the support arms includes a central horizontal portion 12a terminating at one end in a vertical extension 12b which is rotatable within a sleeve 24 rigid with the step 10. In order to support the sleeve 24, and thereby support the step 10, on the support arms 12, a collar or shoulder 13 is formed on the lower end of the vertical extension 12b which is adapted to abut the lower end of

25 the sleeve 24. Thus, when the extension 12b is inserted into the sleeve 24, the lower end thereof is supported on this shoulder 13. To retain the arm extension 12b within the sleeve 24, the extension is equipped at its upper end with a collar 26. The collar is fixed to the extension as by a set screw 26a and bears against the upper end of the sleeve. Adjacent the other end, each of the support arms inclines upwardly and terminates in a horizontal portion 12c turned laterally outward, which portion is adapted for engagement with the inner surface

40 of the window casing F. For this purpose, rigid with the extremities of the outer portions 12c of the support arms 12, are internally threaded collars 28 in which are received complementally-threaded shank portions 30a of casing-engaging feet 30. In addition to the threaded shank portions, each of the feet includes a resilient pad 32, which is preferably of hemispherical form for engagement with the window casing F so as to prevent marring thereof, and a finger-piece 34 by means of which the position of the foot 30 with respect to the arm 12 and its collar 28 can be adjusted. It will be seen that by such adjustment of the feet window frames or walls of different thicknesses can be accommodated and leveling of the window platform structure can be readily effected.

In carrying out one important aspect of the invention, means is provided whereby the sill-engaging feet 14 are automatically positioned for engagement with the window sill S as an incident to lateral swinging movement of the support arms 12 to adjust the device to the width of the window or similar opening in which it is to be installed. For this purpose, the sill-engaging feet 14 are slidably mounted on the support arms 12 and are adjusted toward and away from the pivotal connections 12b, 24 of the arms 12 with the step 10 by means of links 36 pivotally interconnected between the step 10 and the feet 14. As shown, each of the links 36 includes a generally horizontal

70 central member 36a disposed somewhat above and in a plane parallel to that of the corresponding support arm

12 and terminates at its ends in vertically disposed sleeves 36b adapted to receive pivot pins 38 and 39. The pivot pins are carried respectively by the feet 14 and the step 10. Each of the pivot pins 39 is disposed forwardly of the corresponding pivotal connection 12b, 24 for the corresponding support arm 12 and extends downwardly parallel to the pivotal axis thereof. Referring now to Fig. 7, it can be seen that each of the feet 14 includes a cross fitting 40 having horizontal and vertical bores therethrough. The pivot pins 38 are respectively mounted in the upper ends of the vertical bores of the fittings 40. Axially slideable within the horizontal bores of the fittings 40 are the portions 12a of the support arms 12. For engagement with the window sill S each of the feet 14 preferably includes a roller 42 which is rotatably supported in the lower end of the vertical bore of the cross fitting 40. The roller 42 is desirably provided with a flange 42a intermediate its ends. The upwardly projecting portion of the roller 42 extends into the lower vertical end of the cross fitting 40, the latter being supported on the flange 42a when the foot 14 is positioned on the window sill S.

Means are desirably provided to prevent the loss of the roller 42 when the window platform is being transported, such means being shown, for example, as an annular groove 43 adjacent the lower end of the roller 42 cooperating with a pin 43a projecting inwardly from the fitting 40. The flanged form of the members 42 is advantageous in that either the flange or the downwardly projecting cylindrical portion of the roller can be used for supporting engagement with the sill S, and in the former case the downwardly projecting cylindrical portion serves as an inward movement limiting abutment for engagement with the outer face of the sill. While it is not necessary that the members 42 be rotatably supported, to do so is desirable in that it permits them to roll along the sill as the positions of the support arms 12 are adjusted thereby facilitating the adjustment of the device upon installation in a window opening.

Upon reference to the drawings and to Fig. 2 in particular, it will be seen that as the support arms 12 are swung toward and away from each other, by virtue of the sliding connections between the feet 14 and the portions 12a of the support arms, the positions of the feet are automatically adjusted by the links 36 so that the flanged members 42 are automatically positioned for engagement with the window sill S. In other words, the length of the links 36 and the disposition of the pivotal connections thereof with the step 10 and with the feet 14 are such that the perpendicular distance between the axis of the feet 14 and the axis of the support arm portions 12c is substantially constant within the useful range of adjustment of the device. Minor variations in this length, as for example, variations in frame and wall thickness or disposition, can be readily accommodated by appropriate adjustment of the casing engaging feet 30 with respect to the support arm portions 12c.

In carrying out another aspect of the present invention, means is provided whereby the instant window platform can be locked in any position of adjustment so as to prevent accidental dislodgment after the device has been installed. For this purpose, means is provided for locking the support arms in any position of adjustment. More particularly, means is provided for locking the pivotal connections 12b, 24 between the arms 12 and the step 10 in any desired position.

In the present instance, the guard rail assembly 16 and the support arm extension portions 12b are adapted for this purpose. The lower ends of the standards 20 are received in upwardly opening sockets defined by axial bores 44 extending through the support arm extensions 12b. Each of the bores 44 adjacent its lower end is of tapered form having a square or otherwise polygonal cross section. For engagement therewith, there is provided a locking member 46 which is complementally

shaped with respect to the bore 44. The locking member depends from the standard 20 of the guard rail assembly 16, being supported thereon by a locking sleeve 48. The lower end of the standard 20 and the upper end of the locking member 46 are of a frusto-conical form and adjacent their ends are reversely screw-threaded for cooperation with the complementally-threaded sleeve 48. Within the sleeve 48 and interposed between the frusto-conical ends of the locking member 46 and the standard 20 is a 10 collar 50 having a bore 50a therethrough and the ends of which are outwardly flared. The oppositely flared bore 50a of the collar 50 as shown provides surfaces complemental to the frusto-conical ends of the locking member 46 for engagement therewith.

15 From the foregoing it will be seen that upon installation of the guard rail assembly 16 with the step 10, the lower ends of the locking members 46 are inserted in the upwardly opening sockets defined by the bores 44 in the support arm extensions 12b. Upon rotation of the locking 20 sleeve 48, the tapered lower end of the locking member 46 is brought into mating engagement with the complementally tapered portion of the bore 44 thus preventing further rotative movement of the locking member 46. Further rotation of the locking sleeve 48, by virtue of its threaded engagement with the locking member 46 and the standard 20 causes the two frusto-conical ends thereof to be drawn together into gripping engagement with the collar 50 thereby firmly securing the locking member with respect to the standard. The foregoing is accomplished 25 on each side of the guard rail assembly and since the two standards 20 are interconnected by means of the U-shaped guard rail 18, the pivotal connections 12b, 24 are locked in position and there can be no relative movement between the arms 12 and the step 10. Thus, each of the support 30 arms is prevented from being swung inwardly until such time as the guard rail assembly 16 is removed, and therefore accidental dislodgment of the device from installed 35 position in a window is prevented.

I claim as my invention:

40 1. A window platform for mounting in a window frame having a casing and a sill, said platform comprising, in combination, a step, a pair of support arms each pivotally engaged at one end with said step for lateral swinging movement relative thereto, a casing-engaging foot mounted on the other end of each of said arms, a sill-engaging foot slidably supported intermediate the ends of each of said arms, and a link pivotally interconnected between each of said sill-engaging feet and said step for automatically shifting the position of said sill-engaging feet with 45 respect to said arms upon lateral swinging movement of the latter.

2. A platform for mounting in a window or like opening in a building wall comprising, in combination, a step, 50 a pair of support arms, a pivotal connection between one end of each of said arms and said step mounting said arms for lateral swinging movement, the other ends of said arms being adapted for engagement with the building wall adjacent each side of the opening, a foot slidably supported intermediate the ends of each of said arms and 55 adapted to engage the building wall on the bottom of the opening, and means for sliding said feet along said arms as an incident to swinging movement of the latter.

3. A platform for mounting in a window or like opening in a building wall comprising, in combination, a step, 60 a pair of support arms, a pivotal connection between one end of each of said arms and said step mounting said arms for lateral swinging movement, the other ends of said arms being adapted for engagement with the building wall adjacent each side of the opening, a foot slidably supported intermediate the ends of each of said arms and 65 adapted to engage the building wall on the bottom of the opening, a pair of links, and pivotal connections between the ends of said links and said step and between the other ends of said links and said feet whereby said feet are 70 75

automatically positioned with respect to said arms as an incident to swinging movement of the latter.

4. A platform for mounting in a window or like opening in a building wall comprising, in combination, a step, a pair of support arms, a pivotal connection between one end of each of said arms and said step mounting said arms for lateral swinging movement, the other ends of said arms being adapted for engagement with the building wall adjacent each side of the opening, a foot slidably supported intermediate the ends of each of said arms and adapted to engage the building wall on the bottom of the opening, means for sliding said feet along said arms as an incident to swinging movement of the latter, and means for locking said pivotal connections in any position of adjustment of said arms with respect to said step.

5. A platform for mounting in a window or like opening in a building wall comprising, in combination, a step, a pair of support arms each having an angularly disposed end portion, means rigid with said step for receiving said arm end portions to define a pivotal connection between each of said arms and said step mounting said arms for lateral swinging movement, the other ends of said arms being adapted for engagement with the building wall on the sides of the opening, a foot slidably supported intermediate the ends of each of said arms and adapted to engage the building wall on the bottom of the opening, means for sliding said feet along said arms as an incident to swinging movement of the latter, a guard rail assembly including a rail and a pair of standards mounting said rail in spaced relation above said step, and means interposed between said guard rail assembly and said support arm end portions for locking said pivotal connections in any position of adjustment of said arms with respect to said step.

6. A platform for mounting in a window or like opening in a building wall comprising, in combination, a step, a pair of support arms each having an angularly disposed end portion, a pair of sleeves rigid with said step for receiving said arm end portions to define a pivotal con-

nexion between each of said arms and said step mounting said arms for lateral swinging movement, said arm end portions having bores therein defining sockets, the other ends of said arms being adapted for engagement with the building wall adjacent each side of the opening, a foot slidably supported intermediate the ends of each of said arms and adapted to engage the building wall on the bottom of the opening, means for sliding said feet along said arms as an incident to swinging movement of the latter, and a guard rail assembly including standards adapted for reception in said sockets.

7. A platform for mounting in a window or like opening in a building wall comprising, in combination, a step, a pair of support arms having angularly disposed end portions, sleeves rigid with said step and journaling said arm end portions so as to define pivotal connections between said arms and said step mounting said arms for lateral swinging movement, the other ends of said arms being adapted for engagement with the building wall on the sides of the opening, a foot slidably supported intermediate the ends of each of said arms and adapted to engage the building wall on the bottom of the opening, means for sliding said feet along said arms as an incident to swinging movement of the latter, and means for locking said pivotal connections in any position of adjustment of said arms with respect to said step including a member non-rotatably engageable with each of said arm end portions.
